(57) CLAIM

The ornamental design for a trailer as shown and described.

DESCRIPTION

FIG. 1 is a top, rear, right side perspective view showing my new design for a trailer;

FIG. 2 is a top, front, left side perspective view thereof;

FIG. 3 is a top plan view thereof;

FIG. 4 is a right side sectional side view thereof taken along line 4-4 in FIG. 1;

FIG. 5 is a left side cross-sectional view thereof taken along line 5-5 of FIG. 1;

FIG. 6 is a rear cross-sectional view thereof taken along line 6-6 in FIG. 1;

FIG. 7 is an enlarged view thereof taken from area 7 in FIG. 1;

FIG. 8 is an enlarged view thereof taken from area 8 in FIG. 4;

FIG. 9 is an enlarged view thereof taken along line 9-9 of FIG. 4;

FIG. 10 is a bottom view thereof;

FIG. 11 is a front end view thereof;

FIG. 12 is a left side view thereof; and,

FIG. 13 is a right side view thereof.

The dash-dash broken lines illustrate portions of the trailer which form no part of the claimed design.

The dash-dot broken lines depict boundaries of the enlarged views which form no part of the claimed design. The dash-dash broken lines showing cross-sectional views and enlarged views form no part of the claimed design.
